TEST TUBE RACK

John V. Wing, 1610 Longfellow St., Detroit, Mich.

Filed Dec. 10, 1962, Ser. No. 72,790

Term of patent 14 years

(Cl. D16—1)

FIGURE 1 is a top view of the test tube rack.
FIGURE 2 is a front elevation of the test tube rack.
FIGURE 3 is an end view of the test tube rack.
FIGURE 4 is a sectional view taken on line 4—4 of FIGURE 2.

I claim:

The ornamental design for a test tube rack, as shown.
